UNITED STATES PATENT OFFICE

HANS KLASEN, OF COLOGNE-WORRINGEN, GERMANY

RENEWABLE SAFETY FUSE

Application filed March 19, 1927, Serial No. 176,720, and in Germany December 3, 1926.

The present invention has reference to improvements in safety fuses for guarding electrical circuits and apparatus of various kinds, and it relates more particularly to a renewable safety fuse of the plug or cartridge type, 5 and the specific object of the invention is to provide in the safety device a conducting and fusible member in the form of a strip or lamella which is held merely by friction between opposed contact clips and which, upon 10 the fuse having been blown by overload, can readily be replaced by a similar lamella without the use of tools.

My invention will best be understood when 15 described in connection with the accompanying drawing illustrating a preferred embodiment, in which Fig. 1 is a vertical longitudinal section through the safety device; Fig. 2 is a horizontal section, Fig. 3 a plan view, 20 and Fig. 4 a front view thereof.

The cartridge body 1, if insulating (preferably ceramic, material, is provided with a 25 passage 1^a extending therethrough from side to side thereof for the reception of the fusible link lamella 2 and its support clips 3 and 30 respectively. One end 10 of the body 1 is covered by the metallic cap 4, and the other end thereof has a nipple-like extension 100 sheathed by the metallic thimble 40. The 30 front cover 4 is current-conductingly connected with the metallic contact clip 3 by the metallic screw pin 5, and the thimble 40 is electrically connected with the metallic contact clip 30 by the metallic screw pin 50. The 35 pins 5 and 50 may be soldered, riveted, welded, or otherwise current-conductingly secured to the respective cover members 4 and 40. The pins are threaded at their inner ends, and the contact clips 3 and 30 have an internal 40 thread and coat with the pins and act as clamping nuts to retain the contact parts in place. Between the clips a lamella 2 of a suitable fusible material is inserted, whose clamped end portions, after the fuse has 45 blown, can readily be removed for the insertion of a fresh lamella.

By the provision of the passage 1^a extending entirely through the body two open sides are presented through either one of which a 50 fuse may be inserted and removed, thus giv-

ing greater convenience in applying and removing fuses when the fuse holder is arranged in a confined space, as well as greater convenience in assembling the parts of the fuse holder in the factory. In the event also 55 of the sticking of a blown fuse, or of the necessity of adjusting or replacing a clip, where the fuse holder is arranged in a contracted space, these opposite open sides permit of the introduction of the fingers or tools from both sides, so that the fuse may be released 60 and removed or the clip adjusted or repaired with greater ease and expedition.

What I claim is:—

In a renewable safety fuse of the character 65 set forth, in combination, a ceramic body having an opening extending therethrough from side to side thereof, a reduced cylindrical extension integrally projecting from one end face of said body, a metallic cover for said reduced body extension, a metallic cover for 70 the other end of the body face, metallic screw pins extending from the said metal covers through the ends of said body into the opening, metallic contact clips threaded on the 75 inner ends of said screw pins for clamping coaction with the respective metal covers, and a fusible lamella held between said contact clips and adapted to be applied and removed through either side of the opening 80 in the body.

In testimony whereof I affix my signature.

HANS KLASEN.
